DESIGN FOR A DRESS

Rhoda Schoen, New York, N. Y.

Application December 9, 1938, Serial No. 81,682

Term of patent 3½ years

To all whom it may concern:

Be it known that I, Rhoda Schoen, a citizen of the United States residing at 525 Seventh Avenue, New York, in the county of New York and State of New York, have invented a new, original, and ornamental Design for a Dress, of which the following is a specification, reference being had to the accompanying drawings, forming part thereof.

Fig. 1 is the front view of a dress ensemble showing my design;

Fig. 2 is a rear view of the ensemble shown in Fig. 1;

Fig. 3 is the front view of the dress section in the ensemble shown in Fig. 1; and

Fig. 4 is a rear view of Fig. 3.

The characteristic feature of my design resides in the combination on the ensemble disclosed of the all-over embroidered bolero of the specific configuration shown in association with an evening dress having an empire waistline, a gathered bodice, and embroidered pockets on the full skirt, as shown.

I claim:

The ornamental design for a dress, substantially as shown and described.

RHODA SCHOEN.
